PLASTIC MOLDED FLOWER POT

Theodor Box, 1108 Aileen Road,
Brielle, N.J. 08730

Filed Dec. 17, 1974, Ser. No. 533,542

Term of patent 14 years

Int. Cl. D11—02

U.S. Cl. D35—3 A

FIG. 1 is an isometric view of a flower pot according to the present invention showing spaced curved rectangular portions on the outer periphery thereof simulating rough hewn wood sectional striations thereon:

FIG. 2 is a top plan view; and

FIG. 3 is a sectional view taken along lines 3—3 of FIG. 1.

I claim:

The ornamental design for a plastic molded flower pot, substantially as shown and described.
